UNITED STATES PATENT OFFICE

TOBIAS J. KAUFMAN, OF CHICAGO, ILLINOIS

LAVATORY FIXTURE

Application filed August 7, 1925, Serial No. 48,743. Renewed March 26, 1927.

This invention relates to combination lavatory fixtures, and especially to fixtures of that class which includes a faucet and soap dish.

5 The invention is particularly adapted for use in connection with the pop-up waste structure embodied in my Patent No. 1,483,490, issued Feb. 12, 1924, although, as will hereinafter appear, it may also be used apart 10 from such structure.

In the manufacture of sanitary lavatory fixtures of the present period, the trend is toward the utilization of china spouts and soap dishes, since they present a more pleasing appearance, are cleaned more easily than metal, and are not subject to tarnish or corrosion. The objectionable feature of the utilization of fixtures made of china is that 15 they are more fragile than metal.

20 In view of the foregoing, it is one of the objects of the present invention to so combine a china spout and soap dish for a lavatory fixture, that the one will operate to strengthen the other against breakage.

25 Another object of the invention is the provision of a composite or integral china spout and soap dish which is also provided with a recess adapted to permit passage therethrough of an operative element of the 30 fixture which supports the dish and spout.

Other objects of the invention will be made apparent in the following specifications, when read in connection with the drawings forming a part thereof.

35 In said drawings:

Fig. 1 is a vertical section through a fixture embodying my invention.

Fig. 2 is a top plan view of the fixture shown in Fig. 1.

40 Fig. 3 is a top plan view of a modified form of the invention.

Fig. 4 is a side elevation of the fixture shown in Fig. 3, a portion of the support being shown in section, and,

45 Fig. 5 is a fragmentary perspective view showing the shank and sleeve in process of assembly.

Now referring specifically to the drawings, in which like reference characters indicate like parts throughout the several

views, A indicates the basin structure, comprising the slab 1, and bowl 2, usually of vitreous china or enameled iron.

Extending through a passage formed in the slab 1 is a screw-threaded metallic shank 55 3, provided with an annular flange 4, resting upon the top of the slab 1, the shank being clamped to said slab by means of a nut 5 threaded onto the shank and bearing 60 on a washer 6.

Mounted above the slab 1 is a casting comprising a china spout 7 and an integrally formed bowl 8, the casting being provided, on the side remote from the spout 7, with an eared projection 9 which is apertured to 65 receive the pop-up waste rod 10 specifically disclosed in my prior patent heretofore referred to. Obviously, however, such aperture may, if desired, receive the valve rod 70 controlling the delivery of water to the spout 7.

As herein illustrated the pop-up waste rod 10 is enclosed by a sleeve 11, provided at its top with an annular flange 12 which rests upon the top of the projection 9. The sleeve 11 is externally provided with screw-threads 75 which cooperate with threads interiorly carried by the shank 3, whereby to secure the sleeve to the shank with the flange 12 firmly seated upon the projection 9. A T-fitting 13 is also secured to the lower end of the shank 3, the rod 10 extending through 80 said fitting and being connected to instrumentalities adapted, upon manipulation of the knob 14, to raise or lower the waste plug, 85 not shown, in the bottom of the bowl 2, as set forth in the patent referred to.

As shown in Fig. 1, the vertical side of the projection 9 is outwardly inclined and the bottom portion thereof, and the bottom portion of the lower wall of the spout 7 is recessed to provide a seat for a rubber gasket 15, which is seated upon the flange 4 carried by the shank. The upper portion of the 95 shank 3 is somewhat enlarged, the top thereof being slightly concaved to provide a seat for a rubber gasket 16, and a lip 17 is integrally carried by the shank and extends 100 into the body portion of the spout 7, with

the instrumentalities arranged as shown in Fig. 1.

In the installation described, the spout 7 is placed over the shank 3, and rests upon the gaskets 15 and 16, the lip 17 aligning with the center of the spout and preventing any continued rotation of the spout structure in any malicious attempt to remove it. The sleeve 11 is then screwed downwardly into the shank until the flange 12 presses upon the top of the projection 9, forcing the lower portion of the projection, and of the spout, against the gasket 15, and the internal peripheral shoulder on the projection 9 against the gasket 16. The nut 5 is then turned upwardly on the shank 3 to firmly secure the spout assembly to the lavatory slab, as will be clearly understood. The water from the supply pipe or pipes, not shown, enters the shank 3 through the T-fitting 13, and passes through the port 3' to the spout 7.

As before stated, the principal objection to the utilization of china spouts is that they are easily broken, the weakest portions being throughout the length of the spout, or at its juncture with the body portion provided with the passage for the water controlling elements. In order to strengthen the spout 30 therefore, and to provide for the usual soap receptacle, I form the cup 8 and the spout 7 as an integral structure, and form reinforcing ribs 18, 18 on the bottom portion of the cup 8, extending in a plane running longitudinally of the spout. Such ribs 18 not only serve to strengthen the spout 7 and the integral cup 8 against accidental breakage, but also facilitate the removal of the soap from the cup, as will be understood.

40 In addition it is to be noted that the lip 17 which extends longitudinally and interiorly of the spout 7, is positioned to receive the first contact of the water which enters the spout. In some cases this water 45 is of a temperature very much higher than the temperature of the spout, and the intense heat of the water is absorbed by the metallic lip 17, thereby preventing breakage of the china spout 7.

50 Figs. 3 and 4 show a modified structure which is similar in all respects to the assembly just described, except that the cup 8 is not extended over the top of the projection 9.

55 From the foregoing it will be clear that I have provided a structure which not only safely permits the utilization of a china spout, but which is possessed of an added advantage, in that it also provides a china cup which is integrally formed as a strengthening member for the spout.

Various modifications of the structure herein set forth will be suggested to those skilled in the art, but my invention covers

all embodiments falling fairly within the scope of the appended claims.

What I claim is:

1. A lavatory fitting comprising a basin, and a supporting slab apertured to receive a movable element, a shank surrounding said element and extending through the aperture and provided with a peripheral flange adapted to clamp the slab and retain the shank in position, a spout in communication with said shank, and a lip carried upon the upper portion of said shank and extending into said spout whereby to limit rotation of the spout with respect to the shank when the latter is clamped in position on said slab.

2. In a lavatory fixture, a unitary casting comprising a spout, an anchoring element extending upwardly from the spout, and a soap dish extending from the anchoring element along the spout, whereby such named parts are mutually reinforced.

3. In a lavatory fixture, a unitary casting comprising a spout, an attaching hub, and a soap dish extending from the hub along the spout, whereby such named parts are mutually reinforced.

In testimony whereof I affix my signature.

TOBIAS J. KAUFMAN.
